UNITED STATES PATENT OFFICE.

WILLIAM TEMPEST, OF MILFORD, MASSACHUSETTS, ASSIGNOR TO HOPEDALE MANUFACTURING COMPANY, OF MILFORD, MASSACHUSETTS, A CORPORATION OF MASSACHUSETTS.

AUTOMATIC FILLING-REPLENISHING LOOM.

1,372,106.

Specification of Letters Patent. Patented Mar. 22, 1921.

Application filed June 23, 1919. Serial No. 305,984.

To all whom it may concern:

Be it known that I, WILLIAM TEMPEST, a citizen of the United States, residing at Milford, in the county of Worcester and 5 State of Massachusetts, have invented certain new and useful Improvements in Automatic Filling-Replenishing Looms; and I do hereby declare the following to be a full, clear, and exact description of the invention, such as will enable others skilled in the art to which it appertains to make and 10 use the same.

This invention relates to automatic filling replenishing looms.

15 One object of the invention is to provide an automatic filling replenishing loom with a bobbin chute of improved construction and arrangement whereby the picker stick is permitted to be operated in its slot with a 20 length of throw which is much greater than is obtainable with the ordinary construction of automatic filling replenishing loom.

A further object of the invention is to provide an automatic filling replenishing 25 loom with a bobbin chute which is mounted on the lay and which is tipped into an operative position under the bobbin at pre-determined times. To these ends the automatic filling replenishing loom is provided 30 with a bobbin chute whose upper portion is pivoted to the lower and which is normally held in an inoperative position entirely out of the path of travel of the picker stick, whereby a much longer throw thereof 35 is obtainable than is possible with the ordinary construction. Provision is also made for automatically and positively swinging the upper portion of the bobbin chute back into an operative position at the time when 40 the weft replenishing mechanism operates to eject the exhausted bobbin, so that as the latter falls from the shuttle it is properly deflected and guided down out of the way. The swinging portion of the bobbin chute 45 is also provided with a beveled end or outer side edge so that if by any chance the bobbin chute should remain in its inclined position across the picker stick slot, it will be forced therefrom and into an inoperative 50 position by the engagement of the picker stick itself with the beveled end, so that under all conditions the extended throw of the picker stick will be uninterrupted.

To the accomplishment of the foregoing

objects and such other objects as may appear, the invention consists in the structure hereinafter described and claimed.

In the drawings which illustrate the preferred embodiment of the invention, Figure 1 is a perspective of a portion of an automatic loom, showing the improved bobbin chute construction; Fig. 2 is a front elevation of the same, and Fig. 3 is a section taken on line 3—3 of Fig. 2 viewed in the direction of the arrows.

The automatic loom may be of any usual or preferred construction, and is provided with the usual weft replenishing mechanism and associated parts. In the drawing all the details of the weft replenishing mechanism are omitted with the exception of the rock shaft 10 extending across the front of the loom frame and which is rocked upon the indication of critical exhaustion of the filling in the filling carrier of the active shuttle, and upon the completion of the next beat up of the lay, the replenishing operation takes place.

The lay 12 is provided with the usual opening or slot 13 in which the picker stick 14 is thrown back and forth as it forces the shuttle 15 across the loom in the weaving operation. The slot 13 is provided with a guide 16 and to which is secured the bobbin chute 17. The bobbin chute 17 consists of two parts: a lower part 18 which is formed integrally with the picker stick guide and forms part of the lay and an upper part 19 pivoted to the lower part 18 upon the pintle 20 and which is adapted to swing about its pivot from an inoperative position as shown in full lines in Fig. 3 into an operative position indicated by dotted lines in Fig. 3. A coil spring 21 serves to yieldingly hold the upper portion 19 of the bobbin chute in its inoperative position. It is to be observed that the upper portion 19 of the bobbin chute is movable to and from a position across the picker stick slot 13, so that when in its inoperative position it leaves a free and unobstructed path for the picker stick 14 to be thrown up to the inner side of the bobbin chute, whereby an increased amount of power can be transmitted to the shuttle in order to force the same across wide fabrics, or even when weaving relatively narrow fabrics an increase in speed of the shuttle can be obtained. The

extent of throw of the picker stick is controlled by a strap (not shown) in a manner well known and familiar to those skilled in the art, so that the picker stick may never 5 be thrown beyond the inner side of the bobbin chute.

The bobbin chute 17 is provided with the usual side flange which in the present instance comprises upper and lower portions 10 23, 24. The upper portion 23 has a lateral ear 25 extended inwardly therefrom and which is adapted to coöperate with an arm 26 mounted on the rock shaft 10 and made fast thereon by the set screw 27. The arm 15 26 is provided with a beveled face 28 for a purpose to be described. When replenishment is indicated, the rock shaft 10 is turned in a clockwise direction viewing Fig. 3. This raises the arm 26 from the full line to 20 dotted line position. The lay then beats forward upon its replenishing beat-up and the ear 25 comes into engagement with the lower portion of the beveled face 28 of the arm 26, and continues to ride up over the 25 face as the lay continues to beat forward. By the time the lay has reached the end of its forward beat, the ear 25 has moved up onto the substantially horizontal upper side of the arm 26. The movement of the ear 25 30 up over the face 28 of the arm 26 causes the upper portion 18 of the bobbin chute to be gradually tilted or swung from its normally inoperative position into an operative position, as indicated in dotted lines in Fig. 3, 35 so that when the lay arrives at the end of its replenishing beat-up, the tip of the upper portion 18 of the bobbin chute is in such a position as to just contact with the lay. At this time the replenishing operation takes 40 place and the exhausted bobbin or filling carrier is ejected from the shuttle and falls downwardly striking the upper portion 18 of the bobbin chute by which it is guided into a receptacle.

45 The lay then starts to beat backward, and the weft replenishing mechanism operates to turn the shaft 10 in an anticlockwise direction (see Fig. 3) whereupon the arm 26 is returned to its initial full line position, 50 and allows the upper portion 19 of the bobbin chute to be returned by means of the spring 21 to its inoperative position. The shuttle is then picked across the lay in the usual manner by the picker stick 14 which 55 operates in a free and unobstructed path.

The coil spring 21 is designed to return the upper portion 19 of the bobbin chute immediately to its inoperative position. If, however, the spring should be broken, or be 60 comes worn out, further provision is made for returning the bobbin chute to its inoperative position, and to this end the outer side edge of the upper portion 19 of the bobbin chute is beveled, so that should the same re-

main in an operative position across the 65 path of the picker stick 14 it will be forced therefrom by the engagement of the picker stick 14 with the beveled side edge, so that the travel of the picker stick will not be interrupted at this particular time. Of 70 course where suitable opportunity is presented, the loom will be stopped so that the broken or otherwise defective spring 21 may be repaired.

The important feature of the invention re- 75 sides in the provision of such construction of a bobbin chute that the throw of the picker stick may not be limited in any way by any portion of the bobbin chute construction.

In the present instance I have illustrated and described the preferred embodiment of the invention, but it is not desired to limit the invention to the exact structure disclosed.

I claim—

1. An automatic loom having, in combination, a bobbin chute mounted on the lay and adapted to be moved into and out of an operative position across the picker stick slot, means coöperating with the bobbin chute to move it into and hold it in its inoperative position out of the path of travel of the picker stick, and means to move the bobbin chute into its operative position and to hold it there during the replenishing op- 95 eration.

2. An automatic loom having, in combination, weft replenishing mechanism, a lay, a bobbin chute pivoted upon the lay and adapted to be swung into and out of an op- 100 erative position across the picker stick slot, a spring coöperating with the bobbin chute to move the same into an inoperative position out of the path of travel of the picker stick, and means operated by the weft re- 105 plenishing mechanism to move the bobbin chute against the tension of the spring into its operative position and to hold it there during the replenishing operation.

3. An automatic loom having, in combi- 110 nation, weft replenishing mechanism, a lay, a bobbin chute pivoted to the lay and adapted to be moved into and out of an operative position, means coöperating with the bobbin chute to move the same out of its operative 115 position, and means operated by the weft replenishing mechanism for moving the bobbin chute into its operative position and holding it there during the replenishing operation, said means including a lug on the 120 bobbin chute, an arm having a beveled face adapted to be engaged by the lug and to cause the same to ride up over the beveled face upon the replenishing beat-up of the lay to swing the bobbin chute into its opera- 125 tive position.

4. An automatic loom having, in combina- 125 tion, weft replenishing mechanism, a lay, a

- bobbin chute pivoted to the lay and adapted to be moved into and out of an operative position across the picker stick slot, means coöperating with the bobbin chute to move 5 the same out of its operative position, and means operated by the weft replenishing mechanism for moving the bobbin chute into its operative position and holding it there during the replenishing operation, said 10 means including means adapted to be moved into a position to engage the bobbin chute as the lay moves forward on its replenishing beat-up to tilt the same into its operative position.
- 15 5. An automatic loom having, in combination, weft replenishing mechanism including a rock shaft, a lay, a bobbin chute mounted thereon movable into and out of an operative position, means coöperating 20 with the bobbin chute to move it out of its operative position, and means actuated by the rock shaft to move the bobbin chute into
- its operative position and to hold it there during the replenishing operation.
6. An automatic loom having, in combination, weft replenishing mechanism, a picker stick, a lay, a bobbin chute mounted on the lay movable into and out of an operative position across the path of the picker stick and provided with a beveled outer side edge 25 adapted to be engaged by the picker stick and to be forced thereby out of its operative position, and means to move the bobbin chute into its operative position when replenishment is indicated and to hold it there 30 during the replenishment operation.
7. An automatic loom having, in combination, weft replenishing mechanism, a lay, a bobbin chute mounted thereon and normally maintained in an inoperative position and 35 having provision by virtue of which it may be tilted into an operative position under the bobbin.

WILLIAM TEMPEST.
